UNITED STATES PATENT OFFICE.

EDGAR REGESTER LOWEREE, OF BALTIMORE, MARYLAND.

BED.

1,058,076.

Specification of Letters Patent.

Patented Apr. 8, 1913.

Application filed July 16, 1912. Serial No. 709,748.

To all whom it may concern:

Be it known that I, EDGAR R. LOWEREE, a citizen of the United States, residing at Baltimore, State of Maryland, have invented 5 certain new and useful Improvements in Beds, of which the following is a description, reference being had to the accompanying drawing and to the figures of reference marked thereon.

10 The invention relates to new and useful improvements in beds, and more especially to beds which are adapted for invalids or for performing minor operations.

An object of the invention is to provide 15 a bed construction wherein the portion thereof for supporting the person may be bodily adjusted vertically or wherein one end may be raised and the other end depressed.

A further object of the invention is to provide 20 a bed of the above character wherein the support for the person may be swung relative to the bed frame about a central pivotal point.

A further object of the invention is to provide 25 a bed of the above character wherein the supporting portion for the person is formed in sections, certain of which may be adjusted angularly relative to the other.

These and other objects will in part be 30 obvious and will in part be hereinafter more fully described.

In the drawings, which show by way of illustration one embodiment of the invention: Figure 1 is a perspective view of a bed embodying my improvement, the supporting portion for the person being removed. Fig. 2 is a partial side elevation and a partial sectional view showing the bed with the supporting portion in raised position. Fig. 3 is a plan view of the bed showing the supporting portion turned at an angle to the bed frame. Fig. 4 is a detail in section showing the pivotal support connecting the support for the mattress to the 40 supporting frame therefor. Fig. 5 is a detail in side elevation showing one end of the mattress support raised and the other end depressed.

In carrying out my invention I have provided 45 a bedstead frame which is of the usual construction, consisting of a head frame 1, a foot frame 2, and side frames 3, 3. These parts may be secured together in any desired way so as to form a rigid structure. Mounted on the bedstead frame is a mattress support 4, on which rests a mattress 5. This

mattress is made as herein shown in three sections 6, 7 and 8. The central section 7 is secured to the mattress support by a pivot pin 9. The section 6 of the mattress has 60 two side bars 10 rigidly fixed thereto. These side bars project beyond the section 6 and are pivoted at 11 to the section 7 of the mattress. Likewise side bars 12 are rigidly secured to the section 8 of the mattress and project beyond the same and are pivoted at 13 to the section 7.

The supporting frame 4 for the mattress is preferably formed of angle iron and consists of side and end bars which are rigidly 70 attached to one another and also flat cross-bars which are suitably spaced and riveted to the horizontal members of the side bars forming the mattress support. As clearly shown in Fig. 5, the sections of the mattress may be swung to various angular positions relative to each other. The section 6, as shown in this figure, is swung about the pivotal connection 11 and is held in angular or raised position by a supporting bail 14 80 which is pivoted to the outer end of the section 6 and rests on the mattress supporting frame. A wire handle 15 may be secured to the outer end of the section 6 to facilitate the raising and lowering of the 85 same. In this figure the section 5 of the mattress is swung about the pivot pins 9 and is held in this angular position by the lower end or edge of the section 8 of the mattress which rests on the supporting 90 frame. It will be obvious that other adjustments of the sections of the mattress relative to each other and the supporting frame may be made.

While I have used the term "mattress," 95 it will be understood that this term is used in its broadest sense and is intended to include the use of covered spring sections, tufted felted sections, or any other desired form of construction.

The mattress support 4 is carried directly by a supporting frame 16 which, as herein shown, is formed of angle bars or irons which are rigidly attached together. Said frame also includes a crossbar 17 which is 100 rigidly secured at its outer end to the crossbar forming a part of the supporting frame. These angle bars are so shaped that the upper edges of the vertical flanges lie in a horizontal plane. The mattress support is 110 attached to this supporting frame by a pivot bolt 18. This pivot bolt extends through

the central crossbar secured to the mattress support and also through a central crossbar 17 carried by the supporting frame. A sleeve 19 encircles the pivot bolt and forms a rest for the crossbar of the mattress support, as shown in Fig. 4. A nut 20 is threaded onto the pivot bolt 18 and retains the mattress support on the supporting frame. This connection between the mattress support and the supporting frame permits the mattress support to be turned about the pivot bolt 18 as a center. The upper edges of the angle bars forming the supporting frame 16 engage the crossbars on the mattress support and serve as a means for preventing the tilting of the mattress support on its pivot. In other words, the mattress support 4 rests on the frame 16 and the pivot bolt 18 merely serves to guide the mattress support as it is swung on the frame and also holds the mattress support on the frame.

While I have shown the supporting frame 16 as rectangular, it will be obvious that this frame may be made circular or any other shape. While I have shown a pivot bolt for connecting the mattress support to the frame 16, it will also be obvious that other forms of pivotal connections may be used.

The supporting frame 16 is connected to the bedstead frame by devices which may be used for bodily raising and lowering said supporting frame relative to the bedstead frame. These devices in the present embodiment of my invention consist of two pairs of parallel links or bars 21 and 22. The links 21 and 22 at one side of the bedstead frame are secured to the same pivot bolt 23, while the links 21 and 22 at the opposite side of the bedstead frame are secured to a similar pivot bolt 23. The lower ends of the links 21 are connected to a crossbar 24 which projects beyond said links. An inclined track or guide 25 is attached to the bedstead frame and the projecting end of the rod 24 extends into said track or guide. There is a similar guide or track for each end of the rod 24. This guide is formed of a U-shaped bar which is secured at one end to the side frame of the bed. Said guide is arranged at an angle to the side frame and its other end is attached to the head frame of the bed at a point below the attachment of the side frame thereto. The links 22 are attached to a crossbar 26. The ends of the crossbar project beyond the links 22 and engage tracks or guides 27 which are similar in shape to the guide 25, but incline in opposite directions thereto.

The supporting frame 16 is raised by drawing the crossbars 25 and 26 toward each other along the supporting guides or tracks therefor. The means for moving the rods 25 and 26, as herein shown, consist of a cen-

tral shaft 28 which is mounted in suitable brackets 29 carried by the side frames of the bed. This central shaft is formed with laterally projecting arms 30 and 31. There are two arms 30 and these arms are located adjacent the outer ends of the shaft but inside the supporting brackets therefor. There are likewise two arms 31 which are similarly disposed. Each arm 30 is connected by a link 32 to the crossbar 26, while each arm 31 is connected by a link 33 to the crossbar 24. It will be apparent that when the shaft 28 is rotated so as to move the laterally projecting arms from a horizontal position, as shown in Fig. 1, to a vertical position, as shown in Fig. 2, that the crossbars 25 and 26 will be moved toward each other and thus raise the supporting frame 16 bodily from the bedstead frame. When the shaft 28 is turned in an opposite direction the crossbars 25 and 26 will be moved away from each other and allow the supporting frame 16 to be lowered. As a means for holding the shaft 28 in various positions I have provided a ratchet wheel 34. A pivoted locking pawl 35 is adapted to engage the ratchet wheel and hold the shaft 28 from rotating. The locking pawl 35 is provided with a finger piece 36 which projects below the side frame of the bed and serves as a handle for throwing the pawl out of engagement with the ratchet wheel. Each end of the shaft 28 is formed with a squared portion 37 adapted to receive a crank 38.

From the above description it will be apparent that the frame 16 is pivotally connected with the links 21 and 22. In order to hold this frame from turning about this pivotal connection, I have provided a pair of links 39 which are pivoted at one end to the supporting frame, and at their other end to the outer end of the arms 31. These links are so disposed relative to the links for raising and lowering the supporting frame as to hold said supporting frame in substantially horizontal position when raised and when in lowered position. The links will also hold this supporting frame substantially horizontal while it is being bodily raised from lowered position to raised position. I have, therefore, provided means for bodily raising the mattress support from the bedstead frame to raised position without tilting the same or without moving the same endwise relative to the bedstead frame. When the supporting frame is either in lowered position or in raised position the mattress support may be swung about its pivotal connection therewith. When in lowered position the ends of the mattress support will swing between the bars forming the end frames. Furthermore, it will be noted that when the supporting frame is in lowered position, as shown in Fig. 1, the crossbars 24 and 26

have moved down the inclined tracks or guides and are, therefore, positioned in a plane below the plane of the supporting frame 16. This positioning of the crossbars aids greatly in the initial raising of the supporting frame 16, for the reason that the links 21 and 22 are at an angle to each other rather than in a line and, therefore, said bars may be drawn toward each other.

- 10 When it is desired to raise one end of the supporting frame and depress the other, the shaft 28 is turned in a reverse direction from the position shown in Fig. 1. This movement of the shaft 28 carries the laterally projecting arms 29 below the shaft and as the links 39 are pivoted to the outer ends of these arms 29 the end of the frame 16 to which the links 39 are attached will be held down or depressed, while the central portion 20 of the frame 16 will be raised, which results in a tilting of the frame 16, as shown in Fig. 5. The links 39 are each formed with a deflected portion 40 which permits this swinging of the arms 29 without the links coming 25 into contact with the operating shaft 28.

From the above description it will be apparent that I have provided a bed construction which consists of few parts and which can, therefore, be cheaply made and easily 30 kept in order. This bed construction also permits of the bodily raising and lowering of the supporting portion for the person and also the swinging of this supporting portion at an angle to the bed frame. By these 35 adjustments the supporting portions of the bed for the person may be quickly adjusted for such conditions as may arise either in a case of sickness or in the performing of minor operations.

40 It is obvious that minor changes in the details of construction and arrangement of the parts may be made without departing from the spirit of the invention as set forth in the appended claims.

45 Having thus described my invention, what I claim is:

1. The combination of a bedstead frame, a mattress support, and means for raising and lowering said support relative to said 50 bedstead frame, said means including a supporting frame and means for connecting said mattress support to said supporting frame, whereby said support may be swung horizontally relative to said bedstead frame.

55 2. The combination of a bedstead frame, a mattress support, a supporting frame for said mattress support, means for pivotally connecting said mattress support to said supporting frame, and devices connected to 60 said bedstead frame and to the mattress supporting frame for bodily raising and lowering said supporting frame.

3. The combination of a bedstead frame, a mattress support, and means for raising 65 and lowering said support relative to said

bedstead frame, said means including a supporting frame, means of pivotally connecting the mattress support to said supporting frame, links pivotally connected to said supporting frame at their upper ends and having sliding connection with the bedstead frame at their lower ends, and means for moving the lower ends of said links toward and from each other.

4. The combination of a bedstead frame, a mattress support, means for raising and lowering said support relative to said bedstead frame, said means including a supporting frame for said mattress frame, links pivoted to said supporting frame at their upper ends and having their lower ends slidingly supported by the bedstead frame, a central shaft, projecting members carried by said shaft, and links connecting said projecting members with the sliding ends of the links connected to the supporting frame.

5. The combination of a bedstead frame, a mattress support, and means for raising and lowering said support relative to said bedstead frame, said means including a supporting frame, means for pivotally connecting the mattress support to said supporting frame, links pivotally connected to said supporting frame at their upper ends, said links being arranged in pairs and projecting in opposite directions, a crossbar connected to each pair of links, inclined guides for slidingly supporting said crossbars, a central shaft, projecting members carried by said shaft, and links connecting said projecting members to said crossbars, whereby when said shaft is rotated the crossbars will be moved on said guides.

6. The combination of a bedstead frame, a mattress support, a supporting frame for said mattress support, links pivotally connected to said supporting frame at opposite sides thereof, said links projecting in opposite directions and having a sliding connection with the bedstead frame, a central shaft, oppositely projecting members carried by said shaft, links connecting said projecting members to the links connected to the supporting frame, and links connecting said projecting members directly to the outer edge of said supporting frame.

7. The combination of a bedstead frame, a mattress support, a sectional mattress mounted thereon, means for pivotally connecting the sections of the mattress, a supporting frame for said mattress support, means for pivotally connecting the mattress support to said supporting frame, means for raising and lowering said supporting frame, including links pivotally connected with said frame, and devices for preventing said supporting frame from tilting on its pivotal connection with said links as said supporting frame is raised and lowered.

8. The combination of a bedstead frame, 130

- a mattress support, a supporting frame to which said mattress support is pivotally connected, means for raising said supporting frame, including links pivoted to each side of said frame and extending in opposite directions, a crossbar at each end of the bedstead frame to which said links are connected, guides connected to the frame and inclined relative thereto on which said cross-bars slide, a central shaft, arms projecting radially from said shaft, links connecting said arms with the crossbars, and links connecting one end of the supporting frame to the projecting arms, whereby said supporting frame may be held from tilting when said frame is raised and lowered by turning the shaft in one direction and whereby one end of the frame is depressed when said shaft is turned in the opposite direction.
9. The combination of a bedstead frame member, a mattress-supporting member, means for raising and lowering said mattress-supporting member relative to the bedstead frame member including devices hav-
- ing a common pivotal point and having a 25 sliding engagement with one of said members, and means for moving said devices toward and from each other.
10. The combination of a bedstead frame member, a mattress-supporting member, 30 means for raising and lowering said mattress-supporting member relative to the bedstead frame member including devices having a common pivotal point and having a 35 sliding engagement with one of said members, means for moving said devices toward and from each other, and a mattress support pivotally connected to said mattress-supporting member, whereby the mattress support may be swung in a horizontal plane relative 40 to the bed frame member.

In testimony whereof, I affix my signature, in the presence of two witnesses.

EDGAR REGESTER LOWEREE.
